CLAIM

The ornamental design for the safety razor handle as shown and described.

DESCRIPTION

FIG. 1 is a front perspective view of a safety razor handle.

FIG. 2 is a rear perspective view thereof.

FIG. 3 is a front view thereof.

FIG. 4 is a rear view thereof.

FIG. 5 is a top plan view thereof.

FIG. 6 is a bottom plan view thereof.

FIG. 7 is a side view thereof; and,

FIG. 8 is a side view thereof, opposite the side shown in FIG. 7.

The broken lines are shown for the purpose of illustrating parts of the article that form no part of the claimed design.

1 Claim, 4 Drawing Sheets
